BAND-PASS FILTER NETWORK

Harold A. Wheeler, Great Neck, N. Y., assignor to
Hazelton Corporation, a corporation of Delaware

Application May 23, 1938, Serial No. 209,442

7 Claims. (Cl. 178—44)

This invention relates to multiple-transformer selector systems for the transmission of a broad band of frequencies and, while the invention is of general application, it is of particular utility as a phase-correcting network in band-pass signal-translating systems.

The ratio of cutoff frequencies of a transformer filter utilized in a band-pass selector system is limited by the coefficient of coupling of the transformer. It is difficult to construct a transformer in which the coefficient of coupling between its windings is great and the inherent capacitance is small. To obtain a wider pass band, combinations of transformer filters having different pass bands have been utilized.

In many electrical circuits it is desirable to translate signals of a wide range of frequencies through an electrical network with a predetermined phase shift within the network or, in the case of distortionless transmission, with a phase shift in the network directly proportional to the frequency. For example, in the translation and amplification of video-modulated carrier-frequency signals in a television apparatus, it is required to translate signals over a wide band including high frequencies. While it is desired to translate such signals without distortion in each stage of the signal-translating channel, this may not be practicable, so that it is usually necessary to provide phase-correcting circuits in one or more stages of the signal-translating channel. Such phase-correcting circuits may be utilized for the purpose of providing a distortionless overall characteristic for the signal-translating channel or for the purpose of providing a given phase characteristic for one part of the signal-translating channel which is complementary to that of some other part of the channel.

Phase-correcting networks have heretofore been utilized for the purpose discussed above. In utilizing a phase-correcting section or network for a particular type of phase correction, it is usually necessary to select a type of section the phase shift of which varies in a generally desirable manner over the entire pass band of the system in which it is to be utilized and one which also has particularly favorable phase-correcting properties in selected portions of the pass band. In general, the frequency-phase shift characteristics of simple band-pass filters have minimum slope in the middle of the pass band. Therefore, a filter section or network which may have the same pass band and which has a frequency-phase shift characteristic with maximum slope in the middle of the pass band is particu-

larly useful in correcting phase distortion of such a band-pass filter. Such a filter section or network which tolerates substantial shunt capacitance across the terminal circuits thereof is particularly useful in systems comprising circuit elements having appreciable inherent capacitance, such as vacuum tubes having substantial interelectrode capacitance.

It is an object of the invention, therefore, to provide a multiple-transformer band-pass filter network of the type described above, requiring the minimum coefficients of coupling consistent with the required cutoff frequencies.

It is a further object of the invention to provide a simplified multiple-transformer band-pass filter network of the type described above, presenting constant-*k* image impedances at the terminals thereof.

It is another object of the invention to provide a simplified multiple-transformer band-pass filter network for passing a wide band of frequencies and having a nearly linear frequency-phase shift characteristic over the pass band.

It is a particular object of the invention to provide a two-transformer band-pass filter network, the slope of the frequency-phase shift characteristic of which is a maximum at the middle of the pass band.

It is another object of the invention to provide a network of the type described above which will tolerate the maximum possible capacitance across the terminals thereof.

It is a further object of the invention to provide a network of the type described above which will tolerate appreciable capacitance to ground from each junction in the network.

In accordance with the invention, a band-pass filter comprises a plurality of transformers and condensers, each of the transformers having primary and secondary windings and the number of condensers being two more than the number of transformer windings. The transformer windings and condensers are connected to form two ladder networks, one of the networks having the primary windings as series arms thereof and one-half of the condensers as shunt arms thereof, and the other of the networks having the secondary windings as series arms thereof and the other half of the condensers as shunt arms thereof. The reactive constants of the ladder networks are proportioned to secure a continuous pass band between predetermined cutoff frequencies.

In a preferred embodiment, having maximum slope of the frequency-phase shift characteristic

in the middle of the pass band, only two transformers are utilized in the filter network of the invention. In another embodiment of the invention an inductance is connected in parallel or in series with one of the terminal circuits to provide, respectively, constant- k mid-shunt or constant- k mid-series image impedance for the network.

For a better understanding of the invention, together with other and further objects thereof, reference is had to the following description taken in connection with the accompanying drawing, and its scope will be pointed out in the appended claims.

Referring now to the drawing, Fig. 1 is a circuit diagram of a filter network embodying the invention; Fig. 2 is a graph showing the frequency-phase shift characteristic of the circuit of Fig. 1; Fig. 3 illustrates an embodiment of the invention utilized to obtain constant- k mid-series image impedances across the terminals of the filter network; Fig. 4 illustrates an embodiment of the invention utilized to obtain mid-shunt constant- k image impedances across the terminals of the network, while Fig. 5 is a graph showing the image impedance characteristics of the circuits of Figs. 1, 3, and 4.

Referring now more particularly to Fig. 1, there is shown a band-pass filter comprising two transformers, each having primary and secondary windings, and six condensers, the number of condensers being two more than the number of transformer windings, which has maximum slope in its frequency-phase shift characteristic in the middle of the pass band. This filter comprises a first transformer having primary and secondary windings, L_1 , L_1 and a second transformer having primary and secondary windings L_2 , L_2 individually connected in series with the corresponding windings of transformers L_1 , L_1 across a pair of input terminals 10 and a pair of output terminals 11, respectively. Resistors R , R individually connected to input terminals 10 and output terminals 11 represent terminal resistors for the filter or the image impedances of adjacent circuits to which the filter is coupled. Two condensers C_3 , C_3 are provided, one connected in series with the primary coils L_1 , L_1 and the other connected in series with the secondary coils L_1 , L_2 . Additional shunt condensers C_1 , C_1 and C_2 , C_2 are provided for connection across the primary and secondary circuits and between the junctions of the primary and secondary windings and corresponding terminals of the primary and secondary circuits, respectively. The condensers in the circuit of Fig. 1 may be physical condensers or may be comprised in whole, or in part, of the inherent capacitance of other elements of the network or the system to which the network is coupled.

From the description given, it will be seen that the circuit of Fig. 1 comprises essentially two ladder networks, one having primary coils L_1 , L_2 as series arms and condensers C_1 , C_2 , C_3 as shunt arms, and the other having secondary coils L_1 , L_2 as series arms and condensers C_1 , C_2 , C_3 as shunt arms. By the term "ladder network" is meant any filter network having recurrent and alternating series and shunt impedance arms such as that generalized type of structure shown in Fig. 1, page 121, of "Transmission Circuits for Telephonic Communication" by K. S. Johnson, 1927, published by D. Van Nostrand Company.

The frequency-phase shift characteristic of the circuit of Fig. 1 is illustrated in the graph of Fig. 2. It will, of course, be understood that the

reactive constants of the ladder networks are proportioned to secure a continuous pass band between predetermined cutoff frequencies. It is seen that the slope of the frequency-phase shift characteristic of the embodiment of Fig. 1, utilizing two transformers and having properly selected critical frequencies within the band, is a maximum at the center of the pass band. If more than two transformers are utilized, the effect is to cause the characteristic to be more nearly uniform over the pass band. Transformer L_1 , L_1 is more effective in the high-frequency portion of the pass band, while transformer L_1 , L_2 is more effective in the low-frequency portion of the band. Therefore, the slope of the frequency-phase shift characteristic in the upper part of the band can be decreased by increasing the coefficient of coupling of transformer L_1 , L_1 and by decreasing the coefficient of coupling of transformer L_2 , L_2 , and vice versa. In designing a circuit to have a characteristic as shown in Fig. 2 for a particular application, the following formulae may be used in connection with the circuit of Fig. 1:

$$h = \frac{f_1}{f_2} = \frac{f_2}{f_3} = \frac{f_3}{f_4} = \frac{f_4}{f_5} = \sqrt{f_5}; \quad k = \frac{1-h^2}{1+h^2} \quad (1)$$

$$Z_i = R \text{ at } f = \sqrt{f_1 f_5} = f_3 \quad (2)$$

$$Z_i = \frac{R f_5}{f} \sqrt{\frac{f^2 - f_1^2}{f_5^2 - f^2}} \quad (3)$$

$$C_1 = \frac{1}{R \omega_5} \quad (4)$$

$$C_2 = \frac{C_1 (1-h^2)(1+h^4)^2}{h^2(1-h^2+h^4+h^8)} \quad (5)$$

$$C_3 = \frac{1-h^4}{h^4} C_1 - C_2 \quad (6)$$

$$L_1 = \frac{(1+h^2)}{2 C_1 \omega_1^2 (1-h^8)} \quad (7)$$

$$L_2 = \frac{1}{2 L_1 C_2 C_3 \omega_2^4} \quad (8)$$

where

Z_i = image impedance at either of terminals 10 or 11

k = coefficient of coupling of each of transformers L_1 , L_1 and L_2 , L_2

and where f_1 , f_2 , f_3 , f_4 , and f_5 are, respectively, the frequencies in the pass band at which the phase shift of the filter of the invention is π , 2π , 3π , 4π , and 5π . The subscripts of a particular angular frequency ω identify it with the corresponding frequency.

The formulae given above with reference to the circuit of Fig. 1 are derived on the basis of equal coefficients of coupling between the two transformers. Equal coefficients of coupling yield substantially symmetrical phase and image impedance characteristics over the pass band when the band is relatively narrow or when the coefficient of coupling is much less than unity. It will be understood that a "relatively narrow" band is one in which the band width is considerably less than the mean frequency of the band. If the band is not relatively narrow and if it is desired to secure symmetrical characteristics over the band, transformer L_1 , L_1 should have a coefficient of coupling somewhat less than that of transformer L_2 , L_2 . It will be understood that more than two transformers can be utilized in

the filter of the invention, in which case additional condensers are utilized and connected according to the system of connection given above. The effect of more than two transformers is to provide a very nearly uniform slope of the frequency-phase shift characteristic between the cutoff frequencies of the filter, except very close to the cutoff frequencies.

It will be understood that relations between critical frequencies other than those given in 10 Equation 1 may be utilized. In proportioning a circuit in accordance with the invention, the circuit is divided into its equivalent lattice networks in accordance with the procedure described in detail in section 15 of "Theory of Electrical 15 Artificial Lines and Filters," by A. C. Bartlett (1931), published by John Wiley & Sons, Inc., New York. The critical frequencies are then determined from the equivalent lattice network. Every critical frequency within the band is one 20 at which the impedance of one of the arms of the lattice network is zero and at which the impedance of the other arm of the lattice network is infinite. The cutoff frequencies are those at which the impedance of one of the lattice arms is zero or infinite and at which the impedance of the other of the lattice arms is finite. This procedure of determining critical frequencies is described in detail in an article entitled "General 25 theory of electrical wave filters," by H. W. Bode, published in the "Journal of Mathematics and Physics," November, 1934. The constants of a 30 circuit of the invention may then be determined from the above conditions.

The circuit of Fig. 3 is similar to that of Fig. 1 and similar circuit elements have been given identical reference numerals. The circuit of Fig. 3 has added inductances L_3 , L_4 connected in series between pairs of terminals 10 and 11, respectively, and the ladder networks of the filter 35 of the invention.

The circuit of Fig. 4 is entirely similar to the circuit of Fig. 3 except that series-connected inductances L_3 have been replaced by inductances L_4 , L_4 connected, as shunt arms of the ladder networks, in parallel with input terminals 10 and output terminals 11, respectively. Each of the ladder networks of the circuits of Figs. 3 and 4 is effective to present a constant- k form of image impedance to the pair of terminals to which it is coupled, the circuit of Fig. 3 being effective to present a constant- k mid-series image impedance to each of its pairs of terminal circuits, while that of Fig. 4 is effective to present a constant- k mid-shunt image impedance to each of its pairs of terminals. The image impedance characteristics for the filter networks of Figs. 3 and 4 are shown, respectively, by dotted-line curves 14 and 15 of Fig. 5, while the full-line curve 16 represents the image impedance which is presented to each pair of terminals by the ladder networks of Fig. 1.

In proportioning the circuits including the inductances L_3 , L_3 or L_4 , L_4 of Figs. 3 and 4, respectively, the formulae given above are not applicable. The circuits are proportional in accordance with the general theory outlined above by resolving the networks into their equivalent lattice sections. The added series inductance L_3 in the circuit of Fig. 3 has the maximum possible value consistent with the given image impedance and band width, namely,

$$L_3 = \frac{R}{\Delta\omega}$$

while the shunt capacitance C_1 in the circuit

of Fig. 4 likewise has the maximum possible value,

$$C_1 = \frac{1}{R\Delta\omega}$$

where $\Delta\omega$ is the width of the pass band in angular frequency. The phase characteristics of the circuits of Figs. 3 and 4 are slightly different from those of the circuit of Fig. 1. The differences, however, are minor and do not destroy its value for phase correction purposes.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A band-pass filter comprising a plurality of transformers and condensers, each of said transformers having primary and secondary windings and the number of said condensers being two more than the number of said windings, said windings and condensers being connected to form two ladder networks, one of said networks having said primary windings as series arms thereof and one half of said condensers as shunt arms thereof and the other of said networks having said secondary windings as series arms thereof and the other half of said condensers as shunt arms thereof, the reactive constants of said networks being proportioned to secure a continuous pass band between predetermined cutoff frequencies.

2. A band-pass filter comprising two transformers and six condensers, each of said transformers comprising primary and secondary windings, said windings and said condensers being connected in two ladder networks, one of said networks having said primary windings as series arms thereof and three of said condensers as shunt arms thereof, and the other of said networks having said secondary windings as series arms thereof and the remaining three of said condensers as shunt arms thereof, the reactive constants of said networks being proportioned to secure a continuous pass band between predetermined cutoff frequencies, whereby the slope of the frequency-phase shift characteristic of said filter has a maximum value in the middle of the pass band.

3. A band-pass filter comprising a plurality of transformers and a plurality of condensers, said transformers each having primary and secondary windings and the number of condensers being two more than the number of said windings, said windings and condensers being connected in two ladder networks, one of said networks comprising said primary windings as series arms thereof and one half of said condensers as shunt arms thereof, and the other of said networks comprising said secondary windings as series arms thereof and the other half of said condensers as shunt arms thereof, the reactive constants of said networks being proportioned to secure a continuous pass band and nearly uniform slope of the frequency-phase shift characteristic between predetermined cutoff frequencies.

4. A band-pass filter comprising a plurality of transformers and a plurality of condensers, each of said transformers having primary and secondary windings and the number of said condensers being two more than the number of said

windings, said windings and condensers being connected in two ladder networks each comprising a pair of terminals, one of said networks having said primary windings as series arms and one half of said condensers as shunt arms, and the other of said networks having said secondary windings as series arms and the other half of said condensers as shunt arms, an additional inductance for each of said networks and coupled to the pair of terminals associated with the network, the reactive constants of said networks being proportioned to secure a continuous pass band between predetermined cutoff frequencies and to present the constant- k form of image impedance at each of said pairs of terminals.

5. A band-pass filter comprising a plurality of transformers and a plurality of condensers, each of said transformers having primary and secondary windings and the number of said condensers being two more than the number of said windings, said windings and condensers being connected in two ladder networks each comprising a pair of terminals, one of said networks having said primary windings as series arms and one half of said condensers as shunt arms, and the other of said networks having said secondary windings as series arms and the other half of said condensers as shunt arms, additional inductances individually connected in series with each pair of said terminals and the one of said networks associated therewith, the reactive constants of said networks being proportioned to secure a continuous pass band between predetermined cutoff frequencies, whereby the constant- k mid-series form of image impedance is presented by said networks at each of said pairs of terminals.

6. A band-pass filter comprising a plurality

of transformers and a plurality of condensers, each of said transformers having primary and secondary windings and the number of said condensers being two more than the number of said windings, said windings and condensers being connected in two ladder networks each comprising a pair of terminals, one of said networks having said primary windings as series arms and one half of said condensers as shunt arms, and the other of said networks having said secondary windings as series arms and the other half of said condensers as shunt arms, additional inductances individually connected across each of said pairs of terminals, the reactive constants of said networks being proportioned to secure a continuous pass band between predetermined cutoff frequencies, whereby the constant- k mid-shunt form of image impedance is presented by said networks at each of said pairs of terminals.

7. A band-pass filter comprising a plurality of transformers and a plurality of condensers, each of said transformers having primary and secondary windings and the number of said condensers being two more than the number of said windings, said windings and condensers being connected in two ladder networks, one of said networks having said primary windings as series arms and one half of said condensers as shunt arms, and the other of said networks having said secondary windings as series arms and the other half of said condensers as shunt arms, each of said ladder networks including an additional inductance connected as a shunt arm, the reactive constants of said networks being proportioned to secure a continuous pass band between predetermined cutoff frequencies and to present the constant- k mid-shunt form of image impedance at each of said pair of terminals.

HAROLD A. WHEELER.
